HOBBYHORSE

Milburn R. Hutchison, La Jolla, Calif.

Application April 13, 1953, Serial No. 24,462

Term of patent 14 years

(Cl. D34—15)

To all whom it may concern:

Be it known that I, Milburn R. Hutchison, a citizen of the United States of America, residing at La Jolla, in the county of San Diego, and State of California, have invented a new, original, and ornamental Design for a Hobby Horse, of which the following is a specification, reference being had to the accompanying drawings, forming part thereof.

Figure 1 is a side elevational view of a hobby horse, showing my new design; and

Figure 2 is a top plan view thereof.

The opposite side of the hobby horse, not shown, has substantially the same appearance as the side shown in Figure 1.

I claim:

The ornamental design for a hobby horse, substantially as shown and described.

MILBURN R. HUTCHISON.
